UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

TYPEWRITING-MACHINE.

1,388,987.

Specification of Letters Patent. Patented Aug. 30, 1921.

Application filed September 26, 1918. Serial No. 255,761.

To all whom it may concern:

Be it known that I, JOHN A. WHERRY, a citizen of the United States, residing in New Orleans, in the parish of Orleans and State 5 of Louisiana, have invented certain new and useful Improvements in Typewriting-Machines, of which the following is a specification.

My invention relates to work-assembling 10 devices either forming part of typewriting machines having a revoluble platen, or adapted to be used in conjunction with such machines.

The invention is herein disclosed in the 15 form of a collating sheet, which may be of paper, cardboard, celluloid, or other suitable flexible material, said sheet including marginal flaps or short belts which are adapted to be used as alining devices in the collation 20 of work-sheets, but which terminate short of the normal writing surface, so that they do not produce ridges in the paper which would interfere with smooth writing. The cardboard or other sheet may include more 25 than one set of these flaps, so that work-sheets may be held or pocketed in their collated position along each margin in the recesses between the flaps. The cardboard sheet may also include wings which are 30 adapted to be folded down over the flaps. One special advantage of such wings is that when collated sheets held in position by such wings are passed around the platen, the bending of the wings insures that the work- 35 sheets will be firmly gripped, and thus held against any possible displacement. Moreover, the fact that each collated sheet may be held by a separate non-creeping flap additionally insures the collated sheets from 40 "creeping" relatively to each other during the line-spacing operations incident to writing.

Other features and advantages will hereinafter appear.

45 In the accompanying drawings,

Figure 1 is a perspective view partly broken away, showing the collating sheet passed around the typewriter platen and holding a work-sheet.

50 Fig. 2 is a front perspective view of the collating sheet held erect with its wings open and having three work-sheets held in position.

The collating sheet comprises a body 1 55 having a side strip 2, which may be regard-

ed as a belt forming a base to which a series of short belts 3 are attached. These short belts may be, as herein shown, in the form of a series of overlapping plaits 4, each plait comprising a free flap 5 and a base 6, which 60 is suitably fastened to the side strip 2, as by an adhesive substance. These plaits may be of any suitable number and have their bottoms 7 form recesses or pockets at collatable intervals, viz., at such distances apart 65 that work-sheets set with their leading edges in the bottoms of appropriate pockets or recesses will have the proper lines 8 of any forms thereon superposed, with the result that whatever is written on one sheet on a 70 given line will be impressed on the proper line of an underlying work-sheet by means of suitably positioned carbon paper between the sheets. The free flaps 5 of the plaits may be made as short as is convenient, and 75 to enable them to be made extremely short, the side strip 2 may have hinged thereon a wing 9, which may be integral therewith, and which is adapted to be folded over the faces of the work-sheets set in the plaits to 80 hold the flaps down against the work-sheets. The plaits forming the pockets may in some instances be made from a strip of paper folded on itself, and to avoid undue thickness, each pocket will advantageously over- 85 lie only the adjoining pocket, unless work-sheets are to be collated with their leading edges almost but not quite alined. In this latter case, the pockets will be appropriately located and correspondingly formed. More- 90 over, the pocket flaps may be provided with suitable designations, such as numbers, to facilitate the typist in identifying the proper pocket in which to insert a work-sheet.

When the collating sheet with the work-sheets thereon is passed around the platen, so as to fit the curve thereof, as shown in Fig. 1, the wing 9 will be pressed forcibly against the side strip 2, so that it firmly pinches and holds the sheets either directly 95 or through the flaps 5 of the plaits.

In addition to the side strip 2, the collating sheet may include a second side strip 10 also forming part of the same collating sheet. This side strip 10 may be provided with a set of plaits 11 similar in all respects to the plaits 4, and it may be united to the side strip 2 in such a way as to leave a large opening 12 in the collating sheet, this opening corresponding to the space in 110

which writing is to be done. To unite the two side strips 2 and 10, there may be provided an end strip 13 at one end and an end strip 14 at the other end.

5 One of these end strips, preferably the end strip 14 which forms the leading edge of the sheet when inserted at the rear of the platen of the typewriter, is advantageously provided with an end wing 15, which is 10 adapted to be folded down over the side wing 9, and also over a similar side wing 16 which is hinged to the side strip 10, and is adapted to be folded down on said side strip 10 over the plaits 11. The end wing 15 may serve as an end gage and pocket for 15 the outside work-sheet. When the wings 9, 15 and 16 are folded down, as just described, the collating sheet, together with the work-sheets thereon, forms a fairly unitary structure 20 which may be handled easily and inserted into the typewriting machine without any liability of derangement of the sheets. Moreover, the end wing stiffens the leading edge of the collating sheet, and prevents the leading edge of the outside work-sheet from springing out and catching on any part of the mechanism while being inserted into the machine. After insertion 25 into the typewriting machine, the end wing 15 no longer need hold the side wings down, since the curving of the collating sheet binds the side wings against the face of the collating sheet. It will be noted that either 30 of the wings may be utilized as an edge gage for the side edges of work-sheets when being inserted.

In the form herein described, the sheet 1 is primarily designed to be separate from the typewriting machine, and to have the 40 wings 9 and 16 extend substantially throughout its length.

The wings 9 and 16 will often hold the sheets firmly against creeping, even if the feed rolls 17 do not press them against the 45 platen 18, since the curving of the wings backwardly over the face of the collating sheet induces great pressure, especially if the wings are formed as integral extensions of the sheet which forms the body of the 50 collating sheet, as is usually the best and most economical method of making the sheet. In some forms of typewriters, the feed rolls bear against the margins of the sheets, and, therefore, bear against the 55 wings 9 and 16.

Variations may be resorted to within the scope of the invention, and portions of the improvements may be used without others.

Having thus described my invention, I 60 claim:

1. A collating sheet adapted to be curved around a typewriter platen having a face on which work-sheets are adapted to lie, and having a series of recesses into which the 65 ends of the work-sheets are adapted to be

inserted, so that the ends of the recesses engage the ends of the work-sheets to collate them, each recess having one wall adapted to be lifted clear of the face, and a wing on the collating sheet adapted to be folded down over the recess wall to grip the work-sheets when curved around the platen. 70

2. A collating sheet adapted to be curved around a typewriter platen having a face on which work-sheets are adapted to lie, and having a series of recesses at collatable intervals along each side margin and into which the ends of the work-sheets are adapted to be inserted, each recess having one wall adapted to be lifted clear of the face, 80 and a wing on the collating sheet at each side thereof adapted to be folded down over the recess-walls. 85

3. A collating sheet adapted to be curved around a typewriter platen having a face on which work-sheets are adapted to lie, and having a series of recesses into which the ends of the sheets are adapted to be inserted, each recess having one wall adapted to be lifted clear of the face, a wing on the collating sheet adapted to be folded down over the wall, said wing forming an edge gage for a collated sheet, and an end wing adapted to be folded down to hold down the side wing. 90

4. A collating sheet adapted to be curved around a typewriter platen comprising a body having a series of recesses on each margin of the body adapted to lie beyond the ends of the writing line, the bottoms of the recesses adapted to form end gages for collating together work-sheets, and means for holding down the outer walls of the recesses with the work-sheets seated therein. 95

5. A collating sheet adapted to be curved around a typewriter platen comprising a body having a series of recesses on each margin of the body adapted to lie beyond the ends of the writing line, the bottoms of the recesses adapted to form end gages for collating together work-sheets, and a wing for each side forming a device for causing the outer walls of the recesses to grip the work-sheets. 105

6. A collating sheet adapted to be curved around a typewriter platen comprising a body having a series of recesses on each margin of the body adapted to lie beyond the ends of the writing line, the bottoms of the recesses adapted to form end gages for collating together work-sheets, and means for holding down the outer walls of the recesses with the work-sheets seated therein, said body comprising an opening as extensive as the part of the work-sheets on which typewriting is adapted to be effected. 110

7. A collating sheet adapted to be curved around a typewriter platen comprising a body having a series of recesses on each margin of the body adapted to lie beyond the 115 130

ends of the writing line, the bottoms of the recesses adapted to form end gages for collating together work-sheets, and a wing for each margin forming a device for causing 5 the outer walls of the recesses to grip the work-sheets, said body comprising an opening for the work-sheets on which typewriting is adapted to be effected.

8. A collating sheet adapted to be curved 10 around a typewriter platen comprising a body having a series of recesses, said series of recesses formed by a strip plaited on itself lying beyond an end of the writing line and held to the body at the bottoms of the 15 plaits.

9. A collating sheet adapted to be curved around a typewriter platen comprising a body having a series of recesses on each margin of the body lying beyond the ends of the 20 writing line, each series of recesses being formed by a strip plaited on itself and fastened at the bottoms of the plaits to the body.

10. A sheet-holding device adapted to be curved around a typewriter platen having a 25 face on which a work-sheet is adapted to lie, and having a recess on said face into which the end of the work-sheet is adapted to be inserted, said recess having a wall adapted to be lifted clear of said face, a side wing 30 on the device adapted to be folded across the recess-wall, and an end wing adapted to be folded down over the work-sheet and over the end of the side wing.

11. A sheet-holding device adapted to be 35 curved around a typewriter platen having a face on which a work-sheet is adapted to lie, and having, a series of recesses on said face beyond one end of the writing line and into which the end of the work-sheet is adapted 40 to be inserted, each recess having one wall adapted to be lifted clear of the face, a side

wing on the device adapted to be folded down over said walls, and an end wing on the device adapted to be folded down over the side wing to hold it down for the introduction of the device around the platen. 45

12. A collating sheet adapted to be curved around a typewriter platen comprising a body having a series of recesses on each margin of the body beyond the ends of the writing line, the bottoms of the recesses adapted to form end gages for collating together work-sheets, a wing for each row of recesses adapted to be folded down over the outer 50 walls of the recesses to hold the work-sheets 55 therein, and an end wing adapted to be folded down over the side wings to enable the collating sheet to be introduced around the platen.

13. The combination with a collating support adapted to be curved around a typewriter platen, of a series of free flaps fast to said support at intervals and forming end gages by their junctions with the support, and a wing hinged to the support 60 65 adapted to overlie the flaps to hold them down to hold the collated sheets.

14. The combination with a collating support including strips adapted to lie along the margins of work-sheets and adapted to be 70 curved around a typewriter platen, of a series of alined free flaps fast to said support at intervals and forming end gages by their junctions with the support, and a wing 75 hinged to each margin adapted to overlie the flaps to hold them down to hold the collated sheets.

JOHN A. WHERRY.
